CHUSETTS, A CORPORATION OF MASSACHUSETTS

TUNABLE RADIOFREQUENCY TRANSFORMER

Application filed December 1, 1924, Serial No. 753,221. Renewed May 10, 1928.

Our invention aims to provide improvements in radio frequency transformers.

It has been determined, after much experimentation and careful calculation, that in a transformer of the character mentioned the position of the primary coil with respect to the secondary coil is critical for maximum amplification, and this invention has for its object to provide a transformer embodying therein an arrangement of primary and secondary coils capable of producing a much greater amplification than it has heretofore been possible to obtain in transformers of this character.

Another object of the invention is to provide a transformer for a tunable radio frequency apparatus, in which the primary coil is bunched up or concentrated and located in such a position relatively to the secondary coil as to minimize the capacity between the coils, thereby making it possible to produce an apparatus in which a greater transfer of energy will take place than has heretofore been possible.

Still another object of the invention is to provide a rotor or tertiary coil in inductive relation to the secondary coil of the transformer, and connected in one circuit of a multiple element device such as a vacuum tube to lower the effective resistance of the secondary coil of the transformer, thus increasing the transfer of energy taking place in the radio frequency transformer, or the rotor coil may serve as an untuned antenna coil.

Referring to the drawings:

Figure 1 represents a side elevation of a tunable radio frequency transformer embodying our invention, certain portions thereof being broken away and illustrated in section.

Fig. 2 is an end elevation of the transformer as viewed from the right, Fig. 1.

Fig. 3 is an end elevation of the transformer as viewed from the left, Fig. 1.

Like numerals refer to like parts throughout the several views of the drawings.

In the drawings, 5 represents a tube constructed of bakelite, or similar insulation material, and extending around the periph-

ery of said tube adjacent to one end thereof is an annular groove 6 in which a primary coil 7 is wound. The primary coil 7 is bunched up or concentrated and entirely confined within the groove 6 and consists of approximately 24 turns of number 30 D. C. C. wire, the opposite ends of which are connected to binding posts 8 and 9 mounted in the tube 5.

Extending around the periphery of the tube 5 outside of the primary coil 7 and continuing longitudinally therebeyond is a secondary coil 10, preferably consisting of approximately 77 turns of No. 20 D. S. C. wire, the opposite ends of which are connected to binding posts 11 and 12 mounted in the tube 5.

The coils 7 and 10 are preferably separated by a thin layer of suitable sheet material 13, such as paper. A loop 14 is formed in the secondary coil 10 at a suitable point thereon in order that a wire may be secured thereto. The primary and secondary coils are so positioned relatively to each other that the primary coil will be located near the first few turns of the secondary coil and near the low potential end of the latter.

Located within the tube 5 adjacent to the opposite end thereof from that at which the primary coil 7 is located and adjacent to the high potential end of the secondary coil 10 is a short length of tube 15, the latter being rigidly secured to a rod 16 which is mounted to rock in bearing members 17 and 18 mounted in the tube 5. A suitable knob 19 is provided for the rod 16. The tube 15 has grooves 20 and 21 extending around the periphery thereof in which a rotor or tertiary coil 22 is located, a portion of said coil being located in each of the grooves 20 and 21 and in inductive relation to the secondary coil 10. The coil 22 preferably consists of approximately 30 turns of No. 30 D. C. C. wire, the opposite ends of which are secured to terminals 23 and 24 mounted in the tube 15. The terminals 23 and 24 are connected by suitable wires 25 and 26 respectively to binding posts 27 and 28 mounted in the tube 5. The various binding posts of the transformer are connected to the different elements of a tunable

radio frequency type of apparatus in a manner well known to those skilled in the art.

By using a transformer, as hereinbefore described, it is possible to obtain a maximum amount of amplification and the operator is enabled to tune the apparatus sharply, easily cutting out local broadcasting stations and tuning in upon the distant stations.

It will be understood that a transformer embodying therein a primary and secondary coil, arranged as hereinbefore described and eliminating the rotor or tertiary coil may be employed without departing from the spirit of this invention, such construction being set forth in certain of the appended claims. When, however, the rotor or tertiary coil is employed, being connected in the radio apparatus in one circuit of a multiple element device, such as a vacuum tube, the effective resistance of the secondary coil of the transformer is lowered, thus increasing the transfer of energy taking place in the radio frequency transformer.

While we have shown and described a preferred embodiment of our invention we do not wish to be limited thereby, our invention being best defined in the following claims.

We claim:

1. A tunable radio frequency transformer comprising, in combination, a member provided with a groove therein, a primary coil wound in a bunch around said member and confined within said groove and a secondary coil positioned in inductive relation to said primary coil, said primary coil being located near the low potential end of said secondary coil.

2. A tunable radio frequency transformer comprising, in combination, a member provided with a groove therein, a primary coil wound in a bunch around said member and confined within said groove and a secondary coil positioned in inductive relation to said primary coil, said primary coil being located within the first turns of wire at the low potential end of said secondary coil.

3. A tunable radio frequency transformer comprising, in combination, a member provided with an annular groove extending around the periphery thereof, a primary coil wound around said member and confined within said groove, and a secondary coil positioned in inductive relation to said primary coil, said primary coil being located at the low potential end of said secondary coil.

4. A tunable radio frequency transformer comprising, in combination, a tube of insulating material provided with an annular groove extending around the periphery thereof, a primary coil wound around said tube and confined within said groove, and a secondary coil wound around said tube outside of said primary coil and containing longitudinally therebeyond, said primary coil being located

within the first turns of wire at the low potential end of said secondary coil.

5. A tunable radio frequency transformer comprising, in combination, a tube of insulating material provided with an annular groove extending around the periphery thereof, a primary coil wound around said tube and confined within said groove, a secondary coil wound around said tube outside of said primary coil and continuing longitudinally therebeyond, said primary coil being located within the first turns of wire at the low potential end of said secondary coil, and a rotor coil mounted in inductive relation to said secondary coil adjacent the high potential end of the latter.

6. A tunable radio frequency transformer comprising, in combination, a tube of insulating material provided with an annular groove extending around the periphery thereof, a primary coil wound around said tube and confined within said groove, a secondary coil wound around said tube outside of said primary coil and continuing longitudinally therebeyond, said primary coil being located within the first turns of wire at the low potential end of said secondary coil, another tube pivotally mounted within said first named tube adjacent to the low potential end of said secondary coil, and a rotor coil wound around said second-named tube and located in inductive relation to said secondary coil adjacent the high potential end of the latter.

7. A radio frequency transformer comprising, in combination, a compacted primary coil, and a secondary coil positioned with its low potential end adjacent to and in inductive relation with said primary coil.

8. A radio frequency transformer comprising, in combination, a compacted primary coil of superimposed layers of wire, a secondary coil positioned with its low potential end adjacent to and in close inductive relation to said primary coil, and a third coil in variable inductive relation to said secondary coil adjacent the high potential end of the latter.

9. A radio frequency transformer comprising, in combination, a compacted primary coil, and a secondary coil whose low potential end is positioned in close inductive relation with said primary coil, the primary coil being wound to present a small area to the secondary coil.

10. A radio frequency transformer comprising, in combination, a compacted primary coil, and a secondary coil, the low potential end of the secondary coil being positioned adjacent to and in inductive relation to said primary coil, the average diameter of the primary coil being approximately equal to the diameter of the low potential end of said secondary coil.

11. A radio frequency transformer comprising, in combination, a compacted primary

coil, and a secondary coil, the low potential end of which is positioned in inductive relation to said primary coil and adjacent thereto, the length and depth of said primary coil being substantially equal, and its average diameter approximately the same as the diameter of the low potential end of said secondary coil.

12. A radio frequency transformer comprising, in combination, a compacted primary of relatively small gage wire, and a secondary coil of larger gage wire positioned with its low potential end adjacent to and in inductive relation to said primary coil.

13. A radio frequency transformer comprising, in combination, a compacted primary coil, and a secondary coil positioned in close inductive relation to said primary coil, the average diameter of said primary coil closely approximating the internal diameter of said secondary coil.

In testimony whereof we have hereunto set our hands.

GLENN H. BROWNING.
FREDERICK H. DRAKE.
